PAPER TRIMMER

Charles L. Friermood, Springfield, Ohio, assignor to Charles K. Hullinger, receiver for the Ridgely Trimmer Company, Springfield, Ohio, a corporation of Ohio

Application June 27, 1935, Serial No. 28,629

5 Claims. (Cl. 164—84)

This invention relates to improvements in wall paper trimmers, it more particularly relating to that class of trimmers designed to be used in connection with a straight edge and having a rotary disk as the cutting element.

One of the objects of the invention is the provision of simple, effective and improved means for eliminating cutter disk side play by easily made adjustments whereby an erratic "tracking" of the disk is avoided.

Another object of the invention is to provide that with the same parts it is also possible to adjust the cutter disk laterally with respect to the trimmer body and at the same time to remove any tendency for side-play to develop at any new adjustments of the disk.

In the accompanying drawing:

Fig. 1 is an end elevation of a wall paper trimmer in which the improvements are embodied.

Fig. 2 is a side elevation.

Fig. 3 is an enlarged transverse section on the line 3—3 of Fig. 2.

Fig. 4 is a fragmentary sectional view similar to Fig. 3 showing the parts in a differently adjusted working position than that shown in Fig. 3.

Fig. 5 is a perspective view, partly broken away, of an assembly of the parts whereby the improved operation is obtained.

Fig. 6 is a fragmentary sectional view of a portion of the trimmer body only, the section being taken on the line 3—3 of Fig. 2. The scale is the same as in Fig. 3.

Fig. 7 is an elevation on the same scale as Fig.

3 of a detail.

Referring to the drawing, the trimmer body is indicated at 1, and at 2 are shown longitudinally aligned lugs integrally attached to the lower edge of the body 1, each lug being finished on one side 2' to provide a slidable bearing along the vertical edge of a straight edge shown conventionally in broken lines at 3.

The cutter disk is shown at 4 and since the disk is comparatively thin, the usual flanges bushing 5 is employed in the present case, as is also the nut 6 by which the bushing is secured in place on the disk, the flange of the bushing being indicated at 8. The bushing is centrally apertured for a rotative bearing on the cutter axle 7 in the usual manner, but instead of the customary close tolerance necessary for the fit between the bore of the bushing and the axle on which it rotates, which closeness was formerly relied upon to reduce side-play, the present tolerance is more lib-

eral, and a more rapid assembly of the trimmer is provided.

To eliminate side-play without the necessity of a close tolerance with reference to the fit of the bushing with the cutter axle, dependence is placed on an assembly of members that are adjusted to bear against the opposite ends of the bushing 5. The outer side 8' (Fig. 5 only) of the flange 8 of the bushing 5 is finished in parallelism with the threaded end 9 (Fig. 5 only) of the bushing, and the outer side of the nut 6 is also finished at the same time. In the trimmer body 1 is a cavity 10 in which the cutter disk is housed, and from the walls 11 and 12 enclosing the cavity and forming a part of the body are integrally attached transversely aligned bosses 13 and 14. Each of these bosses is centrally apertured and is provided at their ends with interior threads by tapping into the central openings for a suitable distance.

The operation on the interior of the bosses is best seen in Fig. 6 taken in connection with the other views. The boss 14 is bored to provide the opening 15 and the tap is then run into this opening to provide the threads 16 which extend from the outer end of the boss 14 toward the inner end thereof but stops short of extending into the cavity 10. The boss 13 is similarly threaded to provide the threads 17, but from the cavity outward the bore 18 is provided which is larger in diameter than the aligned bore 15 for a purpose which will appear, as in this enlarged bore 18 there is placed a flanged sleeve 19. The sleeve 19 is shown in full lines in Figs. 3 and 4 in place within the boss 13, and in Fig. 6 in broken lines preparatory to being placed in the bore 18 it being seen that the sleeve enters the bore 18 from the cavity 10 and is slidably moved to the left from the broken line position seen in Fig. 6.

It will be noted that the cutter axle 7 is formed of one piece and is comparatively long and is provided with an enlarged diameter extended portion 20 forming a shoulder 21 at the end of which there is a thread 22. The larger portion 20 is adapted to fit comparatively snugly in the bore 15 of the boss 14, while the thread 22 engages the interior thread 16 in the same boss.

In assembly, the sleeve 19 is slipped into place in the bore 18 of the boss 13, and the cutter disk is temporarily held within the cavity 10 of the body 1 along with a washer 23 whose central opening is such that the washer will fit on the axle portion 7. The cutter axle 7 is then inserted through the openings in the boss 14, the portion 7 passing through the washer 23 and the

cutter disk in the order named. The threaded portion 22 of the cutter axle is engaged in the thread 16 and the axle is then screwed inwardly until a temporarily adjusted position is made, 5 which will be when the flat side 4' of the cutter disk is substantially in longitudinal alignment with the finished sides 2' of the lugs 2.

It will be seen in Figs. 3, 4 and 5 that the axle portion 7 extends through the sleeve 19 into the 10 boss 13 but is only indirectly supported by said boss, the axle passing through and being directly supported by an exteriorly threaded thimble 24 which is centrally bored as at 24' to receive the axle 7. The threaded thimble 24 is shown in detail in Fig. 7. At one end, the threads are removed to form the reduced diameter portion 25 which in assembly projects into the bore. 15

When the threaded thimble 24 is in its place as shown in Figs. 3 and 4 and is screwed inwardly in the boss 13 to a sufficient distance, the shoulder 26 seen on the threaded thimble makes contact with the sleeve 19 and forces this sleeve slidably in the bore 18 until the flanged end 19' of the sleeve 19 bears against the side 8' 20 of the disk bushing 5. This pressure forces the cutter disk to make contact with the washer 23 which then is stopped by the shoulder 21 on the cutter axle 7. 25

It can be seen that two adjustments can be 30 made whereby the position of the cutter disk may be varied and all side play thereof eliminated at any adjusted position. A lateral adjustment is sometimes necessary, as the customary factory adjustment is to provide that the flat 35 side 4' of the cutter disk 4 is substantially in longitudinal alignment with the finished side 2' of the body lugs 2, as mentioned in connection with the previous statement that this alignment is a temporary adjustment during assembly. 40

To make the lateral adjustment as for instance to move the cutter disk laterally to the left, the thimble 24 is unscrewed while the cutter axle 7 is screwed inwardly to follow up the outward movement of the thimble 24. It is easily 45 seen that to move the disk laterally to the right, the cutter axle 7 is unscrewed and the thimble 24 is screwed inwardly.

In Fig. 3 an adjustment is shown which is known as the factory adjustment wherein the 50 cutter disk is substantially as far to the left as it should be placed, but owing to differences in the straight edges on which the trimmer might be used, it is likely that the cutter disk should be moved laterally to the right to avoid a rubbing of the cutter disk against the vertical side 3' of the straight edge 3. The space seen between the flat side 4' of the cutter disk and the straight edge in Fig. 4 is shown in an exaggerated manner. It will also be noticed in Fig. 4 that there 55 is a small clearance space between the flange 19' of the sleeve 19 and the inner surface of the wall 11 and also between the washer 23 and the inner surface of the opposite wall 12, showing the range of lateral movement possible for the 60 cutter disk. 65

To adjust to eliminate side play, the thimble 24 or as the case may be the cutter axle 7, is screwed inwardly to the extent that the cutter disk is clamped between the sleeve 19 and washer

but not to the extent that free rotation of the cutter disk is prevented. When a proper adjustment is found, the parts may be locked in place by use of the set screws 27 in the bosses 13 and 14. 5

Having thus described my invention, I claim:

1. In a paper trimmer, a body having a recess, an axially adjustable axle formed of one piece carried by said body and extending across said recess, a cutting disk in said recess and loosely mounted on said axle, a shoulder on said axle to adjust said disk laterally in one direction with relation to the walls of said recess, and adjustable means carried by said body to adjust said disk laterally in the opposite direction. 10

2. In a paper trimmer, a body having a recess, an axially adjustable axle carried by said body and extending across said recess, a cutting disk in said recess and loosely mounted on said axle, a shoulder on said axle to adjust said disk laterally in one direction with relation to the walls of said recess, and adjustable means carried by said body to adjust said disk laterally in the opposite direction, 20 said last-mentioned adjustable means comprising a flanged sleeve slidably mounted on said axle together with a device for moving said sleeve. 25

3. In a paper trimmer, a body having a recess, an axle carried by said body having a threaded connection therewith so as to be axially adjustable, a cutting disk in said recess and loosely mounted on said axle, a shoulder on said axle to adjust said disk laterally in one direction with relation to the walls of said recess, a flanged sleeve slidably mounted on said axle to adjust 30 said disk in the opposite direction, and an adjustable member having a threaded connection with said body member and a shoulder to engage 35 said sleeve to slide the same on said axle. 40

4. In a paper trimmer, a body having a recess and a pair of aligned oppositely extending trunnions, an axle having a threaded connection with one of said trunnions and extending across said recess into the opposite trunnion, a cutting disk 45 loosely mounted in said recess on said axle, said axle having a shoulder to adjust said disk laterally in one direction, a flanged sleeve loosely mounted on said axle in the trunnion which is located on the opposite side of said disk from said shoulder, and a member having a threaded connection with said last mentioned trunnion and also having a shoulder to engage said sleeve. 50

5. In a paper trimmer, a body having a recess and a pair of aligned oppositely extending trunnions, an axle carried by one of said trunnions 55 and having a threaded connection therewith so as to be capable of axial adjustment, said axle extending across said recess and loosely into the opposite trunnion, a cutting disk located in said recess and loosely mounted on said axle, a sleeve 60 slidably mounted on said axle in said last mentioned trunnion, the inner end of said sleeve having a flange, a screw in said last mentioned trunnion having a shoulder to engage and move said sleeve, said axle having a shoulder on the opposite 65 side of said disk from said sleeve and a loose washer between said last mentioned shoulder and said disk.

CHARLES L. FRIERMOOD.
